UNITED STATES PATENT OFFICE.

WILLIAM C. AVIS, OF NORTH KANSAS CITY, MISSOURI, ASSIGNOR OF ONE-FOURTH TO CHARLES F. SCHOOLING AND ONE-FOURTH TO EDWARD RAYMOND BELL, BOTH OF KANSAS CITY, MISSOURI.

RAIL-JOINT.

1,270,768.

Specification of Letters Patent.

Patented July 2, 1918.

Application filed November 23, 1917. Serial No. 203,536.

To all whom it may concern:

Be it known that I, WILLIAM C. AVIS, a citizen of the United States, residing at North Kansas City, in the county of Clay, State of Missouri, have invented certain new and useful Improvements in Rail-Joints, of which the following is a full and exact specification.

The present invention relates to improvements in rail-joint construction, and aims to devise a joint adapted to provide a substantially even and continuous tread surface throughout the length of the joint. To this end I provide a joint having the ball portions of the rail ends overlapped by cutting the balls diagonally at an angle to the webs of the rails, leaving the webs entire and bolting them together the full length of the joint. By means of the present construction I also aim to provide a joint serving to hold the rails securely in proper alignment, this being accomplished by so cutting away and matching the ball and base flange portions of the rail ends that the web of each rail end is engaged by portions of the ball and base flange of the other rail end and thereby locked against vertical displacement. A further feature of improvement will be found in the construction and manner of mounting the fish plates for abutting against the webs of the rail end portions and for retaining said plates in proper fixed position.

With these general objects in view as well as minor improved details as will appear in the course of the following detailed description, the invention will now be described with reference to the accompanying drawing illustrating one form of construction which has been devised for embodying the same, after which the novel features will be set forth and defined in the appended claims.

In the drawing—

Figure 1 is a side elevation of a rail joint constructed in accordance with the present invention;

Fig. 2 is a sectional plan view taken on the line 2—2 of Fig. 1;

Figs. 3 and 4 are enlarged transverse sectional views taken on the lines 3—3 and 4—4, respectively of Fig. 1;

Fig. 5 is an inverted plan view of one of the rail end portions;

Figs. 6 and 7 are views, on a reduced scale, in plan and side elevation, respectively, of a

rail showing only its end portions and the manner of cutting away said end portions as required by the present improvements; and

Fig. 8 is a plan view of two rail ends assembled ready for attachment of the fish- 60

Referring to the drawing in detail, this illustrates two rails 10, each of which has the ball 12 of its end portion cut away along a line 14 extending diagonally at an angle to 65 the web 16 of the rail and partly across said web so as to expose a portion of the upper edge of the web (see particularly Figs. 3 and 7). Each rail also has the base flange 18 of its end portion cut away along a line 20 70 parallel to the line 14, thereby exposing a portion of the lower edge of the web 16 opposite the exposed portion of its upper edge (see Fig. 5). By cutting away the ball and base flange along the lines 14 and 20, 75 respectively, this also leaves the ball and flange of each rail end, at what may be termed the inner end of its cut away portion, projecting sufficiently to engage the upper and lower exposed edges of the web of the 80 other rail end, and thus in effect pocketing these portions of the webs and serving to lock the rail ends against any tendency to relative vertical displacement. At the inner end of each cut away portion the ball of each rail is provided with a shoulder 22 adapted to abut against the ball terminal of the other rail (see Fig. 8), and the base flange of each rail is formed with a similar shoulder 24 85 adapted to abut against the flange terminal of the other rail when the parts are assembled in joint relation, this construction tending further to stiffen the parts of the joint and prevent any relative movement thereof. 90

The ends of the rail as thus constructed 95 are secured together by means of fish plates 26 and 28 fastened by means of a series of bolts 30 to the opposite faces of the rail ends. When secured in this relation the web portions of the rail ends will extend at a slight angle with reference to the longitudinal line of the rails as shown in Fig. 2, and since the webs are left entire and extend side by side throughout the overlapped ends of the rails it is apparent that this affords double supporting strength to the joint. The fish plate 26 is provided with a horizontal plate portion 32 extending beneath the rail ends and resting on the ties 34, and the free margin of said plate portion 32 is formed with an up- 100 105 110

wardly inclined supporting surface 36 presented in abutting relation to the similarly inclined lower edge surface of the fish plate 28 (see Figs. 3 and 4), this arrangement 5 assisting in preventing any outward sliding movement of the plate 28 under pressure from above. Each of the fish plates 26 and 28 is also provided at one of its ends with inwardly projecting lug formations 38 (see 10 Figs. 1 and 4) extending into engagement with the rail fillets and also abutting against the end of the corresponding web 16.

It will thus be apparent that a simple and efficient arrangement and construction have 15 been devised for carrying out the desired objects of the invention. With the rail webs left entire throughout the overlapping ends of the rails a double-strength joint is obtained, and by means of the pocketing 20 formation whereby each rail embraces a portion of the web of the other rail, the ends of the rail are locked against any tendency to relative vertical movement, and the parts are securely held in this relation by the 25 scribed bolt and fish plate construction. A continuous smooth tread surface is thus provided throughout the length of the joint for the purpose of eliminating as much as possible all jolts and jarring due to gapping 30 or uneven joints which are so ruinous to both the rails and the rolling stock and so undesirable for numerous other reasons.

While the foregoing represents what is 35 regarded as the preferred form of embodiment of the improvements, the right is reserved to such formal changes as may fairly fall within the scope of the claims appended hereto.

What I claim is:

40 1. A rail joint comprising rail end portions having their base flanges cut away on opposite sides and the webs of said end portions left entire and arranged in overlapping relation, the ball of each of said rail end 45 portions being cut away diagonally at an angle to the plane of the web and partly across the same, thereby exposing a portion of the top of the web of each rail end portion and bringing it into engagement with 50 an overlying portion of the cut away side of the ball of the other rail end portion.

2. A rail joint comprising rail end portions having the webs thereof left entire and the webs and balls of said end portions arranged 55 in overlapping relation, the base flanges of said rail end portions being each cut entirely through by a single diagonal cut extending at an angle to the plane of the web and partly across the same and terminating at the end of the corresponding rail 60 end portion, thereby exposing a portion of the lower edge of the web of each end portion for bringing it into engagement with

an underlying portion of the cut away side of the flange of the other rail end portion 65 and leaving each web with a supporting flange extending at one side thereof throughout the length of the web.

3. A rail joint comprising rail end portions having the webs thereof left entire and arranged in overlapping relation, the balls and base flanges of said end portions being each cut away by a single diagonal cut extending entirely through said balls and flanges and at an angle to the planes of the 75 webs and partly across the same and terminating at the end of the corresponding rail end portion, thereby exposing portions of the upper and lower edges of the webs for bringing said exposed portions of each web into engagement between portions of the cut away sides of the ball and base flange of the other rail end portion and leaving each web with a supporting flange extending at one side thereof throughout the length of the 85 web.

4. A rail joint comprising rail end portions having the webs thereof arranged in overlapping relation, the balls and base flanges of said end portions being cut away 90 diagonally at an angle to the planes of the webs and partly across the same, thereby exposing portions of the upper and lower edges of the webs and bringing said exposed portions of each web into engagement between portions of the cut away sides of the ball and base flange of the other rail end portion, and fish plates secured to the opposite faces of the joint and provided with inturned portions in engagement with the 95 fillets of the rails and abutting against the ends of said webs.

5. A rail joint comprising rail end portions having the webs thereof arranged in overlapping relation, the balls and base flanges of said end portions being cut away 100 diagonally at an angle to the planes of the webs and partly across the same, thereby exposing portions of the upper and lower edges of the webs and bringing said exposed portions of each web into engagement between portions of the cut away sides of the ball and base flange of the other rail end portion, and fish plates secured to the opposite faces of the joint and provided with inturned portions engaging the fillets of the rail and abutting against the ends of said webs, one of said fish plates having a horizontal plate portion extending across beneath the rail joint and provided with an 110 upwardly inclined margin in abutting relation with the bottom edge of the other fish plate.

In testimony whereof I affix my signature.

WILLIAM C. AVIS.
